Patented Dec. 17, 1918.

INVENTOR.

George E. Thompson

BY *George E. Webster*

ATTORNEY.

UNITED STATES PATENT OFFICE.

GEORGE E. THOMPSON, OF STOCKTON, CALIFORNIA.

GAS-STOVE.

1,288,289.

Specification of Letters Patent. Patented Dec. 17, 1918.

Application filed May 23, 1918. Serial No. 236,255.

To all whom it may concern:

Be it known that I, GEORGE E. THOMPSON, a citizen of the United States of America, residing at Stockton, in the county of San Joaquin and State of California, have invented certain new and useful Improvements in Gas-Stoves; and I do declare the following to be a clear, full, and exact description of the same, reference being had to the accompanying drawings, and to the characters of reference marked thereon, which form a part of this application.

This invention relates to improvements in stoves, particularly that type in which gas is used as a fuel. The primary object of the invention is to produce a stove having an inner and an outer radiating drum whereby all the heat from the gas burner will be radiated into the room in which the stove may be located. In order to accomplish this, it is necessary that the device be provided with a carefully arranged air inlet means and discharge outlet from the inner drum whereby the cool air may be admitted thereto and, when heated, discharge readily therefrom.

A second object of the invention is so to construct the stove that it will be easily and cheaply assembled and adjusted for operation, since the proper assembling and adjusting is a vital consideration in producing a perfect stove of the type contemplated.

A still further object of the invention is to produce a simple and inexpensive device and yet one which will be exceedingly effective for the purposes for which it is designed.

These objects, I accomplish by means of such structure and relative arrangement of the parts as will fully appear by a perusal of the following specifications and claims.

The figure of the drawings is a vertical section through my improved stove.

Referring now more particularly to the characters of reference on the drawings, I first provide a base chamber 1 preferably of cast metal having a groove 2 in its upper edge. I also provide a top 3, also preferably made of cast metal, provided with a central orifice 4 having a removable covering grate 5.

The numeral 6 designates the primary air cup which is provided in its lower end with a threaded orifice 7 for a purpose as will appear. Extending inwardly from the upper periphery of this cup 6 are lugs 8

centrally orificed to receive bolts 9 which extend through the top 3. The upper edge of the cup 6 is provided with a groove 10, while the top 3 has a groove 11 on its under side alined with such groove 10 and a groove 12 alined with the groove 2. In assembling the device, the primary or outside heating drum or cylinder 13 is fitted into the grooves 2 and 12, while the secondary or inner heating drum or cylinder 14 is fitted into the grooves 10 and 11. The bolts 9 are then inserted through the top 3 and the lugs 8. The nuts 9^a are then tightened. This draws the top 3, drum 14 and air cup 6 tightly together in an efficient manner, as is necessary in a stove of this character.

The numeral 15 designates the main air fitting which is threaded to take into the orifice 7. It is provided with a plurality of branching air pipes 16 which extend to points below the base chamber 1. It is also provided with a vertical air inlet pipe 17 which is threaded as at 18. On this threaded portion 18 is mounted the gas burner shell 19. Such shell has an upper orifice 19^a of a slightly greater diameter than the pipe 17 so as to leave an escape slit from the shell into the base chamber 1. The size of this slit is adjusted by advancing the shell 19 along the threads 18 to bring the sides of the orifices 19^a close toward or away from a beveled base flange 15^a on the fitting 15. In this manner, the size of the slit between the burner and the pipe or fitting may be increased or diminished. On the inner side of the base chamber 1, at the lower edge thereof, is an annular flange 20 forming a seat for the removable base plate 21 which is provided with orifices to fit over the pipes 16 and 17. The base plate 21 is held fitted in position by means of a wing nut 22 which fits over the threaded end 23 of the pipe 17, and engages such plate.

It will be seen that the same nut 22, when tightened, also draws together the top 3, cylinder 13, and base chamber 1, through the medium of the flange 20 resting on the plate 21.

To insure a perfectly tight connection between the drum 14, top 3 and air cup 6, also between the cylinder 13, top 3, and base 1, the grooves 10, 11, 2 and 12 will be partly filled with asbestos or some similar material. An adjustable gate 24 is arranged on the plate 21 around the pipe 17 to control the air supply in the base chamber 1.

A valved pipe 25 supplies the gas to the shell 19 into which it is removably threaded. This pipe extends through an elongated orifice 26 in the side of the base chamber 1 covered by a sliding collar 27 arranged around the pipe 25. This opening 26 is to allow of the pipe 25 being fitted into the shell 19 irrespective of the position in which it may be set on the pipe 17. Auxiliary air intake pipes 28 may be interposed between the outside of the base chamber 1 and the inside of the air cup 6.

In practice, the burner is lighted and the heat from the same causes the air cup 6 to become superheated. This causes the heated air to rise and as it rises it draws into said cup large quantities of cool air through the various air inlets. This air is continuously superheated and passes through the drum 14 and out through the top grate 5. The flames passing between the drums 13 and 14 also cause the heat to be radiated through the drum 13 to the outside thereof and through the drum 14 to the inside thereof, which latter function further heats the air passing from the air cup 6. By means of this construction, practically all the heat in the gas is radiated from the stove into the room in which the stove may be located.

The various fitting connections mentioned permit the stove to be easily and effectively assembled in the manner noted, which is highly essential to the successful operation of the stove.

From the foregoing description it will readily be seen that I have produced such a device as substantially fulfills the objects of the invention as set forth herein.

While this specification sets forth in detail the present and preferred construction of the device, still in practice, such devia-

tions from such detail may be resorted to as do not form a departure from the spirit of the invention, as defined by the appended claims.

Having thus described my invention, what I claim as new and useful and desire to secure by Letters Patent is:—

1. A gas stove comprising a base, outer drum and top, an inner drum and air cup suspended from the top, the top having an opening communicating with the inner drum, a fitting provided with a plurality of air inlet pipes threaded into the under side of the air cup, a beveled flange extending downwardly from said fitting, one of said air inlet pipes being threaded vertically into the flange, and a burner shell adjustably mounted for vertical movement on and surrounding the last named air-pipe, the burner shell being provided with an orifice adjacent the beveled flange and projecting slightly thereover whereby a slit is formed between the flange and the burner, the size of which is adjustable with the moving of the burner on the pipe.

2. A gas stove comprising a base, outer drum and top, an inner drum and air cup suspended from the top, the top having an opening communicating with the inner drum, a fitting threaded into the air cup, a plurality of air inlets carried by the fitting, and a burner arranged below and adjacent the fitting and spaced therefrom to give a communicating slit between the burner and the interior of the base, the burner being adjustable with regard to the fitting whereby the size of the slit formed therebetween may be adjusted.

In testimony whereof I affix my signature.

GEORGE E. THOMPSON.
